UNITED STATES PATENT OFFICE

JOHN H. SHAW, OF NEW HAVEN, CONNECTICUT, ASSIGNOR TO SARGENT & COMPANY, OF NEW HAVEN, CONNECTICUT

LOCK MECHANISM

Application filed June 20, 1930. Serial No. 462,625.

This invention relates to an improvement in locks and more particularly to an improvement in casings or housings for use in connection with pin tumbler locks.

Such locks ordinarily comprise a key barrel and a lock housing or cylinder within which the barrel is received and which contains bores for the reception of the pin tumblers or drivers and the springs by which these elements are actuated. It has been the usual practice to form these housings by casting and to thereafter drill the bores for the tumblers, the ends of these bores being closed by plugs or the like after the cylinder has been loaded.

One object of the present invention is to provide a lock housing for pin tumbler locks which may be manufactured more economically than similar devices in use at this time.

Another object of the invention is the provision of a lock housing made up of a series of flat disks or plates which may be manufactured economically, and which may be assembled with facility so that a complete lock structure may be manufactured more cheaply than is the case with the usual locks of this character.

A still further object of the invention is the provision of a lock case of this character constructed of a series of flat disks or plates which may be readily assembled upon the key barrel, and to provide end sections such that the parts may be assembled between shoulders upon the key barrel and thereby retained against longitudinal movement.

To these and other ends, the invention consists in the novel features and combinations of parts to be hereinafter described and claimed.

In the accompanying drawings:

Fig. 1 is a view of a padlock with the cover removed showing my improved lock to be associated herewith;

Fig. 2 is a front elevational view of the lock unit;

Fig. 3 is a side elevational view thereof; Fig. 4 is a sectional view on line 4—4 of Fig. 2;

Fig. 5 is an elevational view of the key barrel;

Fig. 6 is an elevational view of one of the disks or plates which contain the tumbler recesses;

Fig. 7 is an elevational view of one of the spacer plates;

Fig. 8 is an elevational view of one of the end sections or plates, and

Fig. 9 is an elevational view of a modified form of lock.

While I have chosen to illustrate my improved lock unit in connection with a padlock, it will be understood that its use is not confined to padlocks, but may be used in connection with any lock wherein a pin tumbler lock is desired. A padlock which I selected to illustrate a preferred embodiment of my invention, comprises generally a casing 10, a shackle 11, a swinging bolt 12, a roll back or bolt-actuating member 13 and a lock unit designated generally by the numeral 14. As the specific construction of the padlock is not claimed herein, it will not be necessary to describe in further detail the various features thereof with the exception of the lock unit with which the present application is concerned. This lock unit comprises, in general, a housing 15 designed to contain the usual springs and tumblers and provided with an opening to receive the key barrel 16.

The lock housing 15 is made up of a plurality of flat plates or disks, the thicker disks 17 being designed to house the tumblers and springs and being alternated with the thinner spacing disks or sections 18.

The tumbler plates 17, as shown in Fig. 6, are provided with circular openings 19 within which the key barrel may be received and which are of sufficient size to be slipped over the end of the key barrel opposite the head 20 thereof. Communicating with the central

opening 19 is a slot or recess 21 to receive the tumblers or drivers 22 and the usual springs 23, as it will be understood that the members 17 are assembled upon the key barrel with 5 the slot 21 registering with the key slot 16^a.

Referring to Fig. 4, it will be seen that the plates 17 are of sufficient thickness so that the springs 23 and pins 22 will lie between the planes of the side faces thereof.

10 The spacer plates or disks 18 are shown in Fig. 7, and each of these plates is provided with an opening 24 of the same dimensions as the opening 19 so that they may be slipped over the end of the key barrel. These plates 15 are of sufficient thickness to properly space the pin tumblers at the desired center distances and it will be apparent that when these plates, which are provided with solid body portions above the circular openings 24, are 20 placed against the plates 17, the sides of the recesses 21 will be closed, so as to confine the springs and drivers therein.

It will be noted that, as shown in Figs. 3, 4, and 5, the key barrel is provided with an 25 annular grooves 26 and 27 between which lies the housing for the lock mechanism, the two end plates 17 being flush with the inner ends of these grooves. Two end sections 28 and 29, shown in side view in Fig. 8, are placed 30 at the outer sides of the two end tumbler sections 17. As shown in Fig. 8, these sections have a solid body portion and are provided with semi-circular recesses 30, so that they may be placed laterally upon the key barrel, 35 as distinguished from the sections 17 and 18 which must be slipped over the end thereof.

The recesses 30 are of slightly smaller diameter than the openings 19 and 24 so that the edges of these recesses may enter the 40 grooves 26 and 27 and retain the sections 17 and 18 against longitudinal movement. It will, of course, be apparent that, as in the form shown, the head 20 of the key barrel is slightly larger than the body thereof, the end 45 section 28 may be provided with a circular opening of the same size as the opening 19, as it may be slipped over the small end of the key barrel and lodged against the head thereof and retained in place by the section 29.

50 The thickness of the end sections 28 and 29 may, of course, be varied to suit the conditions obtaining in the particular lock with which they are used, but both of these sections will have solid body portions so as to 55 close the sides of the recesses 21 in the adjacent tumbler sections 17.

It will be apparent that the flat sections of 60 which the lock housing is constructed may be readily and economically made by stamping operations and assembled upon the key barrel with facility and it will also be obvious that they may be loaded as they are assembled and the recesses closed by the intermediate plates. The end sections 28 and 29 may be secured 65 together and to the other sections by pins

or rivets passing through the openings 31, or the lock structure within which my unit is used may be suitably constructed to hold the parts assembled without the use of any securing devices.

In Fig. 9 of the drawings I have shown a modified form of my invention wherein the plates provided with the tumbler-receiving slots 21 are made of relatively thin material and, as shown, two of these plates 17^a and 17^b 70 are placed between the spacer plates 18, the two plates having substantially the same thickness as the single plate 17 shown in Fig. 3. When the plates are made of relatively thin material, as in this instance, they may 80 be stamped out more readily, and when two are placed in juxtaposition, the tumbler-receiving slots will be substantially the same thickness as the tumblers so that the latter may be received in these slots.

85 While I have shown and described a preferred embodiment of my invention, it will be understood that it is not to be limited to all of the details shown, but is capable of modification and variation within the spirit 90 of the invention and within the scope of the appended claims.

What I claim is:

1. A lock housing comprising a series of 95 plates having solid body portions, and a second series of plates disposed between each two adjacent plates of the first series, the plates of said second series having tumbler-receiving recesses extending from face to face thereof, a key barrel upon which said plates 100 are assembled, said key barrel being provided with an annular slot, and one of the end plates of said first series being formed to enter said slot to retain the assembled plates against movement longitudinally of the key barrel.

105 2. A lock unit comprising a key barrel having a series of tumblers therein, a series of plates mounted thereon, each plate having a portion encircling the key barrel, and a slot 110 communicating with the key slot in said barrel, and said plates being assembled on the key barrel with said slots forming a tumbler-receiving recess substantially the width of the tumblers, spacer plates between said first-named plates, said spacer plates also encircling the key barrel and having solid body 115 portions abutting said recesses, and end plates abutting the outside faces of the end tumbler plates, one of said end plates being adapted to be slipped on said key barrel laterally of said barrel and means for securing said plate against movement longitudinally of the barrel.

120 3. A lock unit comprising a key barrel having a series of tumblers therein, a series of plates mounted thereon, each plate having a portion encircling the key barrel, and a slot 125 communicating with the key slot in said barrel, and said plates being assembled on the key barrel with said slots forming a tumbler- 130

receiving recess substantially the width of the tumblers, spacer plates between said first-named plates, said spacer plates also encircling the key barrel and having solid body
5 portions abutting said recesses, and end plates abutting the outside faces of the end tumbler plates, one of said end plates being adapted to be slipped on said key barrel laterally of said barrel and means for securing said plate
10 against movement longitudinally of the barrel, and means for securing said plates together.

In witness whereof, I have hereunto set my hand this 17th day of June, 1930.

15 JOHN H. SHAW.
